Fig-4

FIG 1 is a perspective view of an Easter display showing my new design;

FIGS. 2 and 3 are respectively front and side elevational views thereof, the animals shown in FIG. 1 being omitted for convenience of illustration, it being understood that the animals would normally appear from the front and side; and

FIG. 4 is a rear elevational view of my new design.

An essential feature of my new design comprises the egg-house configuration which forms the background of the display.

I claim:

The ornamental design for an Easter display, as shown and described.
